FIG. 1

FIG. 4

FIG. 5

FIG. 6

FIG. 7

FIG. 8

FIG. 1 is a front perspective view of a sport boat, showing my new design as it would be seen in the water.

FIG. 2 is a top plan view of the sport boat illustrated in FIG. 1 with the sail, mast, standing and running rigging, and control elements omitted for convenience of illustration.

FIG. 3 is a side elevational view taken in the direction indicated on the line 3—3 of FIG. 2.

FIG. 4 is a front elevational view taken on the line 4—4 of FIG. 3 showing those elements omitted in FIG. 2 restored.

FIGS. 5, 6, 7 and 8 are vertical sectional views taken on lines 5—5, 6—6, 7—7 and 8—8 of FIG. 3.

The illustrations in FIGS. 1 and 4 indicate relatively the normal postures of the control devices for the sail and rudders embodied in the sport boat design illustrated in FIG. 1.

I claim:

The ornamental design for a sport boat, as shown and described.
